UNITED STATES PATENT OFFICE.

FREDRICH J. RODE, OF CHICAGO, ILLINOIS, ASSIGNOR TO MARQUETTE TOOL & MFG. COMPANY, OF CHICAGO, ILLINOIS, A CORPORATION OF ILLINOIS.

SHEET-METAL-WORKING PRESS.

Application filed February 7, 1927. Serial No. 166,305.

This invention relates in general to sheet metal working presses, but more particularly to improved means whereby a sheet metal drawing press may be readily converted into a press for performing an entirely different metal working operation such as punching or the like, and vice versa.

In sheet metal drawing presses the material to be operated upon is shaped between two co-operating dies one of which is reciprocable toward and away from the other. A blank or work holding member is provided which co-operates with the reciprocating die for clamping or holding the work therebetween during the shaping or drawing of the metal by the co-operating dies.

The blank or work holding means is resisted in its movement in one direction by cushioning means which causes the blank or work to be gripped with the desired or necessary pressure.

Ordinarily machines of this character when equipped with cushioning means cannot be used for any other purpose than drawing the metal and when the owner of such a press is desirous of performing punching operations, such work must be done on an entirely different press, thereby necessitating the provision of two presses.

It is one of the objects of the present invention to provide improved means whereby a sheet metal drawing press of this character embodying such cushioning means may be readily converted into a press for performing other and entirely different sheet metal operations, such as punching or the like, and vice versa, without necessitating the entire dismantling of the cushioning means or the services of an expert mechanic to thus convert the press.

A further object is to provide in a press of this character improved means for mounting the cushioning means whereby a portion of the cushioning means may be readily raised and lowered into and out of active position and at the same time always remain connected with or suspended from the press.

A further object is to provide connections between the parts of the cushioning means whereby said parts may be readily connected and disconnected when desired.

To the attainment of these ends and the accomplishment of other new and useful objects as will appear, the invention consists in the features of novelty, in substantially

the construction, combination and arrangement of the several parts, hereinafter more fully described and claimed and shown in the accompanying drawings illustrating this invention, and in which

Figure 1 is a view partly in elevation and partly in vertical section of a portion of a sheet metal drawing press constructed in accordance with the principles of this invention, and with the parts in one position.

Figure 2 is a view similar to Figure 1, showing the position of the parts when the press is converted from a drawing to a punching press.

Referring more particularly to the drawings the numeral 10 designates generally the base of a sheet metal press having an upright 11 upon which a member 12 is adapted to be reciprocated in the ordinary and usual manner.

Carried by the reciprocating member 12 is a die 13 which co-operates with a die 14, the latter being supported by a bed plate 15 removably mounted upon the press.

All of the above referred to parts are of the ordinary and well known construction.

Secured to and depending from the press are hanger members 16, any number of which may be provided and these hanger members are preferably in the form of rods 85 having detachable and threaded engagement 17 with the press.

The rods may be of any desired length and in the lower extremity of each of which there is provided a socket or recess 18 opening 90 through the end of the rod.

Arranged below the press is a cushioning device which preferably embodies a cylinder 19 in which a piston 20 reciprocates. Connected with the piston 20 is a piston rod 21 which extends through the closed end of the cylinder and the rod is preferably reduced at its free end as at 22, the reduced portion being adapted to enter the socket or recess 18. A fastening device 23 preferably in the form of a tapered pin passes through registering apertures in the telescoping portions of the rod 21 and hanger member 16 for detachably securing the two together.

Any number of these cylinders and pistons may be provided, one for each of the hangers 16 and when two or more of the cylinders are employed, the piston rods 21 are preferably extended as at 24 to depend below the cylinders, and the extended por-

tions are connected by means of a suitable bar or rod 25 held in position by means of nuts or collars 26 threaded upon the ends of the extensions 24.

5 This rod or member 25 serves to maintain the cylinders and piston in proper position with respect to each other.

10 The pistons 20 are maintained stationary and are held in position preferably by means of nuts or collars 27 which cooperate with a shoulder 28 on the piston rod.

15 Mounted upon each of the hanger members 16 for free sliding movement with respect thereto is a sleeve 29 one end 30 of which contacts with the closed end of the cylinder 19 and the other end of the sleeve is connected by means of suitable fastening devices 31 with a pad or pin plate 32.

20 The sleeve 29 is provided with elongated openings 33 through which openings the fastening device 23 also passes so as to operate therein.

25 Supported by the pad or pin plate 32 are pins 34 upon which a draw ring or blank holding member 35 is supported. This blank holder 35 encompasses the die 14 and is adapted to cooperate with the die 13 to clamp the work 36 therebetween.

30 Fluid pressure is supplied to the cylinders 19 from any suitable source preferably through a pipe 37 which is connected to the piston 20 so as to deliver the fluid pressure through the piston 20 and between the piston and the head of the cylinder 19.

35 When the fluid is admitted into the cylinder, the cylinder 19 will be raised with respect to the piston 20 and this movement will, through the medium of the sleeve 29, raise the pad or pin plate 32 and thereby 40 position the blank or work holding member 35 with respect to the die 14 so that the upper surface of the member 35 will be substantially flush with the top of the die 14.

45 When the ram or member 12 is lowered the die 13 cooperates with the member 35 to clamp the work therebetween and a further lowering movement of the die 13 will shape the work over the die 14. At the same time the member 35 will be depressed 50 against the fluid pressure in the cylinder 19 by lowering the pad or pin plate 32 and the sleeve 29.

55 When it is desired to convert the press from a sheet metal drawing press into a press for performing another and different metal working operation such as a punching operation, the member 35 is first removed and then the pins 34 may be removed, after which the die 14 and bed plate 15 are re-

60 moved. An eye bolt 38 may then be connected with the pad or member 32. A chain may then be connected with the eye bolt 38 and the pressure pad or plate 32 is held up to the opening in the bed of the press.

65 This will also hold the sleeve 29 which is at-

tached to the bottom of the pressure pad or member 32.

The pipe 37 may then be detached from the piston 20. The cylinder 19 and piston 20 together with the piston rod 21 is then lowered to a position under the press or may be carried away from the press.

70 The fastening devices 23 are then placed in position in the opening in the hanger member 16 so that the ends of the fastening device will enter the slot 33 in the sleeve 29.

75 The pad or pin plate 32 is then lowered until the ends 39 of the slots 33 contact with the fastening device 23 (see Figure 2), so that the pad or plate 32 and the sleeve 29 will be suspended by the hanger member 16. 80 This will prevent the pressure pad or member 32 and sleeve 29 from dropping down into the pit beneath the press.

85 A plate 40 having an opening 41 is then placed upon the bed 10 of the machine, with the opening 41 registering with the opening 42 in the bed of the machine.

90 A die 43 having an opening 44 therein is then placed upon the bed plate 40 and the die 13 is interchanged with a punching die 45.

95 If desired a chute 46 may be placed under the opening 42 in the bed of the machine so as to catch the punchings from the work 47 and deflect them away from the machine.

100 Obviously when it is desired to re-convert the press from a punching press as shown in Figure 2 to a drawing press as shown in Figure 1, the die 43 and plate 40 are first removed together with the chute 46. The pad or pin plate 32 and sleeve 29 may be raised by means of a chain, the fastening devices 23 removed and the cylinders and 105 pistons raised until the reduced end 22 passes into the socket 18 in the end of the hanger member 16, after the pin or fastening device 23 is placed in position to connect the parts. The pipe 37 is then connected 110 and fluid admitted to the cylinder so as to hold the pin plate or pad 32 elevated while the chain is being detached. The dies are interchanged and the member 35 and pins 34 placed in position.

115 While the preferred form of the invention has been herein shown and described, it is to be understood that various changes may be made in the details of construction and in the combination and arrangement of the several parts, within the scope of the claims, without departing from the spirit of this invention.

120 What is claimed as new is:

125 1. A sheet metal press embodying interchangeable cooperating dies, a work holding element co-operating with one of said dies for clamping and holding the work therebetween, a stationary hanger connected with the press, cushioning means for resisting the 130

movement of said element in one direction and embodying a cylinder and piston, means detachably connecting the piston with said hanger, means operatively connecting said cylinder with the said element and embodying a sleeve slidable upon the said hanger, and means for supplying fluid to the cylinder, a portion of said connecting means serving to retain the said sleeve upon the said hanger when the cylinder and piston are detached from the press.

2. A sheet metal drawing press embodying co-operating dies one of which is reciprocable towards and away from the other, a work holding element co-operating with the reciprocable die to clamp the work therebetween, a fluid pressure cushion for resisting the movement of said element in one direction, a hanger member supported by the press, said cushion embodying a cylinder and piston, a piston rod, means embodying a fastening member passing through said hanger and piston rod for detachably securing them together, a pressure plate, and a sleeve slidable upon the said hanger member and connected with said plate, said sleeve engaging the cylinder for moving the latter in one direction, there being an elongated opening in the sleeve through which the said fastening member passes, whereby said fastening member will support the sleeve upon the hanger when the cylinder and piston are removed.

3. A sheet metal press embodying a work holding element, a cushion for resisting the movement of said element in one direction, said cushion embodying a pressure pad and a relatively movable cylinder and piston, a hanger member connected with the press, a piston rod detachably connected with the hanger member, a sleeve interposed between the said pad and cylinder and engaging both, said sleeve freely slidable upon the said hanger member and operating to impart a relative movement to the cylinder and piston when said pad is moved, and means carried by the said hanger member and projecting into the path of movement of a portion of said sleeve to maintain the sleeve upon and for supporting the sleeve by the hanger member when the piston rod is detached from the hanger member and said rod and cylinder are removed.

4. A sheet metal press embodying a work holding element, a hanger member connected with the press, means for resisting the movement of said element in one direction and embodying a pressure pad, a sleeve freely slidable upon the hanger member and engaging said pad, a cylinder and piston one of which is detachably connected with said hanger member and the other being engaged by the said sleeve whereby a relative movement will be imparted to the cylinder and piston when said pad is moved, there being

a shoulder on said sleeve, and means connected with the hanger member and projecting into the path of movement of said shoulder in one direction, said shoulder being normally maintained out of contact with the last said means.

5. A sheet metal drawing press embodying a work holding element, means for yieldingly resisting the movement of said element in one direction and embodying a pressure pad, a hanger supported by the press, a cylinder and piston, a rod connected with the piston, said hanger and rod being telescopically connected, a fastening member passing transversely through said telescoping portions for detachably securing the rod and hanger together, and a sleeve freely slidable upon the hanger between and having contact with said pad and cylinder, there being an elongated opening in and extending in a direction lengthwise of said sleeve and within which opening a portion of the said fastening member operates, the end of the slot being adapted to engage said fastening member when the latter is in position and under predetermined conditions.

6. A sheet metal drawing press embodying a work holding element, means yieldingly resisting the movement of said element in one direction and embodying a pad, a hanger supported by the press, a cylinder and piston, a piston rod telescoping with the hanger, a sleeve freely slidable upon the hanger, said sleeve engaging the said pad and cylinder, there being an elongated opening in the sleeve extending in a direction lengthwise thereof, and a fastening element passing transversely through the telescoping portions of the rod and hanger for detachably connecting them, said fastening element extending into said opening and serving to support the sleeve when the cylinder and piston are removed.

7. A sheet metal drawing press embodying a work holding element, means yieldingly resisting the movement of said element in one direction and embodying a pad, a hanger supported by the press, a cylinder and piston, a piston rod telescoping with the hanger, a sleeve freely slidable upon the hanger, said sleeve engaging the said pad and cylinder, there being an elongated opening in the sleeve extending in a direction lengthwise thereof, a fastening element passing transversely through the telescoping portions of the rod and hanger for detachably connecting them, said fastening element extending into said opening and serving to support the sleeve when the cylinder and piston are removed, and means for supplying fluid to the cylinder.

8. A sheet metal drawing press embodying a pressure pad, cushioning means, a hanger member, means detachably connecting the cushion with the hanger and with

respect to which hanger the said pad is movable, a sleeve slidable upon the hanger and interposed between the pad and cushion whereby said cushion will resist the movement of the pad in one direction, and means connected with the hanger and co-operating with said sleeve for supporting said pad and sleeve when the cushion is detached, whereby said press may be converted from a drawing 10 to a blanking or punching press.

9. A sheet metal drawing press embodying a pressure pad, fluid pressure controlled cushioning means, a hanger member, means detachably connecting the cushion with the 15 hanger and with respect to which hanger the said pad is movable, a sleeve slidable upon the hanger and interposed between the pad and cushion whereby said cushion will resist the movement of the pad in one direction, 20 and means connected with the hanger and co-operating with said sleeve for supporting said pad and sleeve when the cushion is detached, whereby said press may be converted from a drawing to a blanking or

punching press, the last recited means embodying a fastening pin like device passing through the hanger for securing certain of the parts together, said pin operating in an elongated opening in said sleeve. 25

10. A sheet metal drawing press embodying a pressure pad, cushioning means, a hanger member, means detachably connecting the cushion with the hanger and with respect to which hanger the pad is movable, means disposed between the pad and cushion and responsive to the movement of the pad whereby the cushion will resist the movement of the pad in one direction, and interengaging means between the hanger and the last said means for supporting the pad and 30 the last said means when the cushion is detached, whereby the press may be converted from a drawing to a blanking or punching press. 35

In testimony whereof I have signed my 40 name to this specification, on this 25th day of January, A. D. 1927.

FREDRICH J. RODE.
